Patented Apr. 3, 1973

226,640

FRAME FOR A MOTORCYCLE

Ramo Vecchi and Carlo Vecchi, San Bartolo Nancalpan,
Mexico, assignors to Acer-Mex., S.A., Mexico, Mexico

Filed May 6, 1971, Ser. No. 141,084

Term of patent 14 years

Int. Cl. D12—11

U.S. Cl. D90—8

FIG. 1 is a side elevation view showing the right side of a frame for a motorcycle in accordance with our design; FIG. 2 is a top plan view thereof; and FIG. 3 is a rear elevational view thereof.

The elements shown in broken lines are included for illustrative purposes only.

We claim:

An ornamental design for a frame for a motorcycle, as shown and described.
